(57) **CLAIM**

The ornamental design for a night light volatile dispenser, as shown and described.

DESCRIPTION

FIG. 1 is a front perspective view from above and to one side of the night light volatile dispenser showing the new design. FIG. 2 is a front view of the night light volatile dispenser of FIG. 1.

FIG. 3 is a back view of the night light volatile dispenser of FIG. 1.

FIG. 4 is a left side view of the night light volatile dispenser of FIG. 1;

FIG. 5 is a right side view of the night light volatile dispenser of FIG. 1.

FIG. 6 is a top plan view of the night light volatile dispenser of FIG. 1; and,

FIG. 7 is a right side view of the night light volatile dispenser of FIG. 1.

The broken line showing in FIGS. 2, 5 and 6 is for illustrative purposes only and forms no part of the claimed design.
